(57) **CLAIM**

The ornamental design for an aerodynamic housing for a rear wheel of a vehicle, as shown and described.

DESCRIPTION

FIG. 1 is a front, top, left side, perspective view of an aerodynamic housing for a rear wheel of a vehicle in accordance with the present invention;

FIG. 2 is a rear, bottom, right side perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a front, top, left side perspective exploded view thereof;

FIG. 10 is a top exploded view thereof; and,

FIG. 11 is a rear, bottom, right environmental view thereof. The dashed and broken lines are for the purpose of illustrating design features and form no part of the claimed design.
